UNITED STATES PATENT OFFICE.

FRANK B. HALL AND ARTHUR F. POOLE, OF WHEELING, WEST VIRGINIA.

TELEPHONE PARTY-LINE SYSTEM.

No. 810,385.

Specification of Letters Patent.

Patented Jan. 16, 1906

Application filed September 23, 1901. Serial No. 76,154.

To all whom it may concern:

Be it known that we, FRANK B. HALL and ARTHUR F. POOLE, of Wheeling, Ohio county, West Virginia, have invented a new and useful Party-Line System, of which the following is a full, clear, and exact description.

Our invention relates to selective party-line systems for telephone-lines, and is designed to overcome the disadvantages incident to such systems as heretofore arranged. These subscriber systems comprise two general classes. In the one class devices are employed at the stations which respond to currents of different strengths and polarity sent from the central station. This system is necessarily limited to a small number of stations on each line and is faulty because of the delicacy of adjustment required and the liability to get out of order. The other class comprises a mechanically-operated step-by-step mechanism located at the substations and actuated by a common current from the central station. In this system a powerful current is necessary to operate all the mechanisms simultaneously, as the stations usually are included in parallel relation. In our improved system only a small current is necessary to operate the selective devices, they being actuated separately and successively. The system can be applied to any party-line without any change in the ordinary telephone condition, and the mechanism at each station is a duplicate of that at all the others.

The invention consists in connecting each station with a continuous line on one side and with a normally broken line on the other side. This system we consider, broadly, new, and it enables us to build up or complete the broken line to any station desired, and thus complete the circuit through such station. The stations are normally connected with the ground, and the invention further consists in providing automatic switch mechanism at each station, which when actuated by a current sent over the broken line to ground will open the ground-circuit and connect the broken-circuit sections between the several stations to form a continuous metallic-sided line to the station desired.

The invention also consists in a new system for locking out all other subscribers in the party-line by the act of removing the receiver at one of the stations.

The invention will be more fully under-

stood by referring to the accompanying drawings, in which—

Figure 1 is a diagrammatic view of a party-line system constructed in accordance with our invention, and Fig. 2 is a detailed view of a plug and switch employed.

Like characters of reference designate like parts throughout the specification.

In Fig. 1 is illustrated a central station and four subscribing-stations A, B, C, and D connected therewith, although the number of substations may be increased. At each station is provided automatic switching mechanism, which, as shown, consists of three electromagnets 2, 3, and 4, arranged in tandem: Armatures 5 and 6 are provided, respectively, between magnets 3 and 4 and 2 and 3, said armatures being normally in the position shown in full lines. Each station is connected with a continuous line-wire F and with a broken line-wire G. The magnet 4 serves to attract the armature 5 to its alternate position to disconnect the ground connection at a substation and to establish continuity of the broken line G.

The circuit through the magnet 4 may be traced as follows: from the wire G to the pivot 7 of armature 5, to contact-point 8, through the magnet 2, through the magnet 4, to ground. The magnet 2 is polarized, the armature thereof being responsive to only one direction of current through the magnet-winding. The circuit from the line-wire F may be traced through the substation as follows: from the wire F to a point 21, from whence two paths may be traced, one path leading to a point 20, to the primary winding 19 of an induction-coil, to transmitter 18, switch-hook 17, contact 16, signal-bell 15, contact-point 14, armature 6 when attracted, and to line-wire G. The other path leads through the windings of magnet 3, contact 9, armature 5 in its alternate position, and to line-wire G. Magnet 3, with the armature 5 in its alternate position, will thus be bridged across the limbs of the line. This magnet is of high impedance and resistance, consequently affording no leakage for voice-currents.

The circuit through the substation from line-wire G normally connects magnets 2 and 4 to ground; but upon current passing through this circuit magnet 4 becomes energized and responds to attract armature 5 to its alternate position, (shown in dotted lines,) the result of this attraction being to open the

circuit through the magnets 2 and 4 by breaking contact 8 with the armature, the armature in its alternate position engaging a contact 23, forming the terminal of the portion 5 of the line-wire G passing on to the next substation. At the next substation magnet 4 is energized in the same manner as in the substation just referred to and the successive portions of the line G between substations 10 are connected together until a complete continuous line is established to the desired substation.

The equipment at the central office consists of a signal-controlling battery 24, a 15 lamp-relay 25, a lamp 26, a clearing-out drop 27, an operator's circuit 28, a station-indicator 29, a signaling-battery 57, and a generator 30. The station-indicator consists of a dial 60, a pointer 61, a ratchet-wheel 62, 20 mounted on the same shaft with the pointer, a pawl 64, pivoted to an armature 65, said armature being adapted to be attracted by an electromagnet 66. The pawl is disposed to actuate the ratchet-wheel upon release of 25 the armature, the armature being drawn back by a spring 67. The electromagnet 66 is connected between binding-posts 32 and 33. Between binding-posts 34 and 35 is placed the ordinary arrangement for supplying 30 talking-current to the transmitters, which consist of a battery 68, impedance-coils 69 for preventing the short-circuiting of voice-currents, and condensers 70 for permitting ready transmission of voice-currents. 35 One side of the cord-circuit includes the clearing-out magnet 27, and when the plug is inserted in the jack the circuits to the line-wires F and G may be traced as follows: from one side of the battery 68 to binding-post 34, to electromagnet 27, to conductor 56, to the tip 51 of the plug, to line F, through the substation apparatus to line G, to jack-conductor 42, to jack-thimble 36, the plug-sleeve 53, conductor 55, binding-post 35, and 40 to the other side of the battery 68, talking-current being thus supplied to the substations. The operator's circuit 28 may be bridged across the plug-circuit to enable the operator to supply current for the operator's 45 talking set.

The plug consists of a sleeve portion 53 and a tip portion 51, insulated from each other, a section of insulating material 52 intervening between the sleeve and the tip portions. This 50 insulating-section upon insertion of the plug in the jack serves to engage the end of spring 42 to disengage said spring from the contact 37. The clearing-out drop 27 consists of an electromagnet and an armature 38, acted 55 upon by a retractile spring 39. Under normal conditions the armature 38 is at a sufficient distance from the electromagnet to prevent attraction thereof by current flowing through the electromagnet, but will be retained against the electromagnet upon being

manually placed in such position. Upon the breaking of the circuit through said electromagnet, however, the armature will be released and pulled against the stop 40 by the retractile spring 39. The binding-post 32 of the indicator is connected to ground through a battery 57, and binding-post 33 of the indicator may be connected to the conductor 55 of the cord-circuit through a switch 43. The generator 30 may be bridged across the 75 strands 55 and 56 of the cord-circuit by means of a switch 45, one side of the generator connecting to ground.

The operation of the system is now apparent. Starting with the line and apparatus in 80 their normal condition, as shown in full lines, suppose that central wishes to call station C. She inserts her plug in the jack and presses the key 43 to establish the following circuit: from the negative side of battery 57 to binding-post 32 of the indicator, through the indicating-electromagnet 66, to binding-post 33, through switch 43, to cord-strand 55, to the sleeve of the plug, to the test-thimble, jack-conductor 42, to line G, to armature-pivot 7, 90 to armature 5, to contact 8, through electromagnets 2 and 4, to ground, and through the ground-conductor at central to the positive side of battery 57. Current flowing in this direction will not operate the polarized electromagnet 2, but will energize magnet 4, causing armature 5 to be moved to its alternate position to engage the alternate contacts 23 and 9. As the circuit is momentarily broken as armature 5 passes to its alternate position, the indicator-electromagnet 66 at the central station becomes momentarily deenergized to allow its armature to be attracted to revolve the ratchet-wheel 63 one division—that is, to bring the pointer to position 1 on the indicator to show the operator that the connections at the first station have been successfully completed. Upon attraction of armature 5 at substation A the circuit through electromagnets 2 and 4 is broken, as also the ground connection, the current from the line-wire G passing directly into the next section of the line-wire G, connecting station A with station B, the same operation taking place at station B as has 115 taken place at station A, and so on. Central now opens the key 43 and closes switch 45, whereby current from the signaling-generator 30 passes through substation C through the following circuit: from generator 30 120 through switch 45, to cord-strand 55, to jack-conductor 42, to line G, to contact 23 of station A, to line-wire G, to contact 23 of station B, to line-wire G, to armature 5 at station C, to contact 8, through magnets 2 and 125 4, to ground, and back through the ground-conductor at central to generator 30. The current from generator 30 is alternating, and polarized electromagnet 2 will now be operated to attract armature 6, and armature 5 130

will also be attracted to its alternate position by electromagnet 4. The operator now opens switch 45 and again closes switch 43 to bring the remaining armatures 5 on the line to their alternate position, whereupon switch 43 is again opened. It will be seen that there is now a complete metallic continuous line between central and the subscriber's signaling apparatus at substation C. Upon closure of switch 45 subscriber C may now be signaled through the following circuit: from generator 30 through switch 45, to cord-strand 55, plug-sleeve 53, jack-thimble 36, jack-conductor 42, line-wire G, armature 5 and contact 23 at station A, armature 5 and contact 23 at station B, to armature-pivt 7 at station C, to armature 6, contact 14, signal-bell 15, contact 16, switch-hook 17, transmitter 18, primary winding 19, to line-wire F, to jack-spring 41, to plug-tip 51, cord-strand 56, electromagnet 27, switch 45, and the other side of generator 30. This circuit is entirely metallic, the grounds at all these substations having been removed by the attraction of armatures 5 to their alternate position. Upon being thus signaled subscriber C removes the receiver from the hook and central connects her talking-circuit to the line, the battery 68 supplying current for both the subscriber and the operator, the circuit from the battery to the subscriber after the removal of the receiver from the hook being traced as follows: from one side of the battery 68 through the clearing-out electromagnet 27, through cord-strand 56, to jack-spring 41, line-wire F, primary winding 19 of the induction-coil at station C, transmitter 18, switch-hook 17, contact 11, contact 13, armature 6, line-wire G, through contacts 23 and armatures 5 at stations B and A, to jack-conductor 42, cord-strand 55, and the other side of battery 68. All the other subscribers on the line are prevented from listening-in on the line, as the armatures 6 at these other stations are out of engagement with the contacts 14 and 13, leading to the substation signaling and talking apparatus. Central having ascertained the party to whom the calling subscriber wishes to talk inserts the plug 72 in the jack of the called subscriber. Should the calling subscriber desire to talk to another subscriber who is party to the line to which he is connected, he is notified by central to press the button 50, thus causing the breaking of the circuit leading to substation C from the line-wire F. Central now closes the switch 46 to connect battery 24 across the line-wires F and G. Electromagnets 3, which are bridged across the sides of the line, are adapted to respond to current flowing from battery 24 to attract the armatures 5 to restore them to their normal position, whereby to break the continuity of the line-wire G and to establish ground connections at each of the substations with the exception of substation C, which by pressure of button 50 has become disconnected from the line. Switch 46 is now open and switch 43 closed; whereby current from battery 57 is led into the ground and to line-wire G to select the party desired 70 to be talked to by substation C, the circuits being the same as hereinbefore traced. After the subscribers have finished their conversation the hanging up of the receivers momentarily breaks the talking-circuit as the 75 switch-hook passes from contact 16 to contact 11, and the clearing-out magnet 27, included in the talking-circuit, momentarily becomes deenergized, allowing the retractile spring 39 to restore the armature 38 to its 80 normal position, thus indicating to the operator that conversation is ended, the operator upon such signal removing the plug from the jack. The operator now closes the switch 46 to again apply current from battery 24 to the line, and electromagnets 3, responsive to the current from said battery 24, attract the armatures 6 and 5 at the substations to return them to their normal position, and the line is now ready for further connections, as herein- 85 before outlined.

As heretofore stated, the electromagnets 3 are provided with windings of high impedance and resistance, the impedance preventing short-circuiting of the talking-circuit when 90 the magnet is connected across the limbs of the line and the high resistance preventing sufficient energization of the electromagnet by the talking-current from the battery 68 or the alternating current from generator 30. 95 The armatures 6 and 5 are only attracted by electromagnet 3 when the battery 24 is directly connected across the line, the circuit through electromagnet 3 being traced as follows: from the positive side of the battery 100 24 through switch 46, to the line-wire F, to a point 21, through the electromagnet 3, to the alternate contact 9, to the armature 5, to line-wire G, through switch 46, and back to the negative side of the battery 24. Upon the 105 closure of the circuit just traced the electromagnets 3 become sufficiently energized to attract the armatures 5 and 6 to restore them to their normal position.

To call central, it is only necessary for the 110 subscriber to remove the receiver from the switch-hook, whereupon the following circuit is established: from the positive side of battery 24, through relay 25, to the relay-armature 47, to the spring-jack contact 37', to jack-spring 41, to line-wire F, to the primary 115 19, to the transmitter 18, to switch-hook 17, contact 11, contact 10, armature 5, contact 8, the magnet 2, magnet 4, the ground, and through the ground-conductor at central, to the negative side of battery 24. Immediately on the closure of this circuit the relay 120 25 becomes energized and attracts the relay-armature 47, whereby a local circuit is established, including the armature 47, signal- 125 130

lamp 26, spring-jack contact 37, jack-spring battery 24, and relay 25, the lamp 26 becoming thus illuminated. Upon energization of relay 25 the armature 47 becomes disengaged from the contact 48, thus breaking the contact of the battery 24 with the line-wire F. This is a very important feature, since it provides an absolute lockout for all the other subscribers, and even if they should take their receivers from the hook to signal central there would be no current flowing through the substation to actuate the signaling device. Upon receiving the signal the operator inserts a plug in the spring-jack, whereby to disconnect contacts 37 and 37' from the jack-conductor 42' and jack-spring 41, respectively, thus breaking the battery-circuit through the lamp 26, and the operator now proceeds to make the connections called for, as hereinbefore described.

The advantages of our invention will be obvious to those skilled in the art. The difficulties inherent in party-line systems heretofore devised are largely overcome, and many of the advantages of a separate line to each station are obtained, and the system can easily be applied to existing party-lines with little expense.

We have shown and described the system as applied to a so-called "common-battery" system, but do not wish to be limited to such application thereof, as it may be applied to a local-battery system with equal advantage. Many changes may also readily be made in the apparatus and circuits employed without departing from the spirit of the invention.

We claim as new, however, and desire to secure by Letters Patent—

1. In a selective party-line system, the combination with a battery, a continuous metallic line, normally open connections leading from said line to a series of stations, automatic switching mechanism at each station, and mechanism arranged to complete the circuit through said connection at any station and then cut out the battery from the continuous line.

2. A central station having a local signal-circuit, a continuous metallic line extending from the central station, connections leading from said line to a series of stations, automatic switching mechanism at each station, mechanism arranged to complete the circuit at any station, a battery normally included in circuit with the continuous line, and means adapted to cut out the battery from the continuous line and to connect it to a local signal-circuit.

3. A central station, a continuous metallic line extending therefrom, a second line extending therefrom and broken at a series of stations, automatic switch mechanism for building up the broken line successively through each station, automatic switch mechanism at each station, including a polarized

magnet and arranged to connect the stations to the metallic circuit, and means at central station for sending a reverse current to actuate the polarized switch system at any desired station; substantially as described.

4. A central station having a step-by-step indicator, a continuous metallic line extending from the indicator, a second broken metallic line extending from the indicator and having a station at each break, a ground-circuit at each station, automatic switch mechanism for building up the broken line successively through each station, and automatic switch mechanism at each station, including a polarized magnet, and arranged to break the ground-circuit and connect the station to the metallic circuit, and mechanism at central station for sending a reverse current to actuate the polarized switch system at any desired station; substantially as described.

5. In a telephone system the combination with a central exchange, of lines extending therefrom to a plurality of substations, telephonic apparatus at each substation, a polarized relay at each substation for controlling the corresponding telephonic apparatus, a non-polarized relay at each substation for controlling the continuity therethrough of one of said lines, current-flow in one direction from the central exchange causing actuation of the non-polarized relays at the substations whereby the line controlled thereby is made continuous to the desired substation, and means upon current-flow in another direction from the central exchange for causing the telephonic apparatus at the desired substation to be connected with the lines upon actuation of the polarized relay.

6. In a telephone system the combination with a central exchange, of lines extending therefrom to a plurality of party-substations, signaling apparatus at each substation, a polarized relay at each substation controlling the connection of said signaling apparatus with the line, one of said lines being normally broken at each substation, a non-polarized relay at each substation for controlling the continuity of the normally broken line, a source of current at the central exchange, current-flow from said source through the lines in one direction causing successive actuation of the non-polarized relays at the substations whereby the normally broken line may be rendered continuous to a desired substation, means upon current-flow from said source through the lines in the opposite direction causing the actuation of the polarized relay at the desired substation whereby the signaling apparatus at said substation is connected with the lines, and means at the central exchange for sending signaling-current through the lines whereby the signaling apparatus at the desired substation may be selectively actuated.

7. In a telephone system the combination

with a central exchange, of lines extending therefrom to a plurality of substations, normally disconnected sections of line connecting the successive substations, a relay at each 5 substation adapted upon actuation to close the line-sections terminating thereat, and means upon current impulse in one direction from the central exchange for causing actuation of the successive relays at the substations whereby the disconnected sections may 10 be connected together to offer a continuous line to a desired substation, signaling apparatus at each substation normally disconnected from the lines, and a second relay at each substation controlling the connection of the signaling apparatus with the line, current impulses from the central exchange in an opposite direction causing actuation of only the second relay at the desired substation where- 15 by the signaling apparatus at this substation is connected with the central exchange exclusive of the signaling apparatus at other substations.

8. In a telephone system the combination 25 with a central exchange, of telephone-lines extending therefrom to a plurality of party-substations, one of said lines being normally discontinuous at each substation, a relay at each substation for controlling the continuity 30 thereof of the normally broken line, signaling apparatus at each substation, a second relay for controlling the connection of said signaling apparatus with the lines and with the central exchange, means at the central exchange for sending current impulse of one polarity into the lines and successively serially through the two relays at each substation until the desired substation is reached, these current impulses causing the actuation 35 of only the first relays whereby said relays are disconnected from circuit and the normally broken line rendered continuous to the desired substation, means at the central exchange for sending impulses into the lines of 40 opposite polarity to cause current-flow of opposite polarity serially through the two relays at the desired substation, the second relay being responsive to this current-flow of opposite polarity whereby the signaling apparatus at the desired substation only is operatively connected with the lines.

9. In a telephone system the combination 45 with a central exchange, of telephone-lines extending therefrom to a plurality of party-substations, one of said lines being normally broken at each substation, a non-polarized relay at each substation adapted upon actuation to close the normally broken line thereat, signaling apparatus at each substation nor- 50 mally disconnected from the lines, a polarized relay at each substation controlling the connection of said signaling apparatus with the lines, said relays being normally connected serially in circuit with the preceding section of the normally broken line and with the

armature of the non-polarized relay, means at the central exchange for sending current impulses of one polarity through a normally broken line, whereby the relays at each substation are successively connected in circuit, 70 said current-flow of one polarity causing actuation only of the non-polarized relay whereby the normally broken line is rendered continuous to the desired substation, means at the central exchange, when the desired substation is reached, for sending a current of opposite polarity over the built-up line, whereby both relays at the desired substation are actuated and whereby the signaling apparatus at the desired substation is connected with the central exchange upon actuation of the polarized relay, and means at the central exchange for sending a signaling-current through the lines to actuate the selected 75 substation signaling apparatus. 80

10. In a telephone system the combination with a central exchange, of telephone-lines extending therefrom to a plurality of party-substations, one of said lines being normally broken at each substation, a non-polarized relay at each substation adapted upon actuation to close the normally broken line thereat, signaling apparatus at each substation normally disconnected from the lines, a polarized relay at each substation controlling the connection of said signaling apparatus with the lines, said relays being normally connected serially in circuit with the preceding section of the normally broken line and with the armature of the non-polarized relay, 90 means at the central exchange for sending current impulse of one polarity through a normally broken line, whereby the relays at each substation are successively connected in circuit, said current-flow of one polarity causing actuation only of the non-polarized relay, 95 whereby the normally broken line is rendered continuous to the desired substation, means at the central exchange, when the desired substation is reached, for sending a current of opposite polarity over the built-up line, whereby both relays at the desired substation are actuated and whereby the signaling apparatus at the desired substation is connected with the central exchange upon actuation of the polarized relay, means at the central exchange for sending a signaling-current through the lines to actuate the selective substation signaling apparatus, and a restoring relay at each substation adapted upon actuation to restore the other relays and circuits to their normal positions. 110

11. In a telephone system the combination with a central exchange, of lines extending therefrom to a plurality of party-substations, signaling apparatus at each substation, a relay at each substation controlling the connection of the signaling apparatus with the lines, one of said lines being normally broken at each substation, a second re- 120 125 130

lay at each substation adapted upon actuation to close the broken line thereat, whereby the broken line may be rendered continuous to any desired substation, a restoring-relay 5 at each substation adapted upon actuation to restore the switch mechanisms of the other relays to their normal positions.

12. In a telephone system the combination with a central exchange, of lines extending therefrom to a plurality of substations, one of said lines being normally broken at each substation, a relay at each substation controlling the continuity of the normally broken line thereat, signaling apparatus at 15 each substation, a second relay controlling the connection of said signaling apparatus with the line, said first and second relays being connected serially in circuit, means upon current-flow in one direction from the central 20 exchange into the first section of the normally broken line for causing current-flow through the first and second relays at the first substation, means for allowing actuation of only the first relay, whereby the first section 25 is directly connected with the following section leading to the second substation, whereby the normally broken line may be rendered continuous to any desired substation, means at the central exchange for sending 30 current impulse of opposite polarity through the built-up line and serially through the first and second relays at the desired substation, said second relay being responsive to the current of opposite polarity, whereby the 35 signaling apparatus at the desired substation is connected with the lines and with the central exchange.

13. In a telephone system the combination with a central exchange, of lines extending 40 therefrom to a plurality of substations, one of said lines being normally broken at each substation, a relay at each substation controlling the continuity of the normally broken line thereat, signaling apparatus at 45 each substation, a second relay controlling the connection of said signaling apparatus with the line, said first and second relays being connected serially in circuit, means upon current-flow in one direction from the central 50 exchange into the first section of the normally broken line for causing current-flow through the first and second relays at the first substation, means for allowing actuation of only the first relay, whereby the first section 55 is directly connected with the following section leading to the second substation, whereby the normally broken line may be rendered continuous to any desired substation, means at the central exchange for sending 60 current impulse of opposite polarity through the built-up line and serially through the first and second relays at the desired substation, said second relay being responsive to the current of opposite polarity, whereby the 65 signaling apparatus at the desired substation

is connected with the lines and with the central exchange, and a restoring-relay at each substation adapted upon actuation from the central exchange to restore the switch mechanisms of the first and second relays to their 70 normal positions.

14. In a telephone system the combination with a central exchange, of lines extending therefrom to a plurality of party-substations, telephonic apparatus at each substation, a source of current at the central exchange, an indicator-relay at the central exchange, actuation of the telephonic apparatus at any substation causing closure of a circuit through said source and said relay, actuation of said relay causing disconnection of said source from the line and connection of said source in a local circuit including an indicating-signal. 75

15. In a telephone system the combination with a central exchange, of telephone-lines extending therefrom to a plurality of party-substations, telephonic apparatus at each substation normally disconnected from the line, a relay at each substation controlling the action of said telephonic apparatus with the line, a source of current and indicating mechanism at the central exchange, actuation of the telephonic apparatus at a calling-substation causing the closure of a circuit through said relay, said source of current and said signaling apparatus, whereby the telephonic apparatus is connected in circuit by the relay, and means upon actuation of the indicating apparatus for causing disconnection of said source from the lines thereby to prevent connection of the telephonic apparatus with the line at other substations. 90

16. In a telephone system the combination with a central exchange, of lines extending therefrom to a plurality of party-substations, telephonic apparatus at each substation normally disconnected from circuit, a relay at each substation controlling the connection of said telephonic apparatus with the 105 lines, a source of current and a relay at the central exchange, means upon actuation of the telephonic apparatus at one substation for closing a circuit through said source of current to said substation-relay and central-exchange relay, actuation of the substation-relay causing connection of the telephonic apparatus with the line and with the central exchange, and actuation of said central-exchange relay causing disconnection thereby 110 of said source from the line and connection of said source in a local circuit with an indicating-signal, the telephonic apparatus at other substations being prevented from connection with the lines upon disconnection therefrom 115 120

17. The combination with a central station, of a line running from said central station broken at a series of substations, electro-magnetic mechanism controlled from the cen- 125 130

tral station adapted to build up a non-inductive circuit through said broken line to any desired substation, a return-circuit from said substations to said central station, electric signaling apparatus at each of said substations, a second line connecting all of said substations with the central station, and electromagnetic mechanism controlled from said central station adapted to connect the said second line with the signaling apparatus at any of said substations, substantially as described.

18. The combination with a central station, of a line running from said central station broken at a series of substations, electromagnetic mechanism controlled from the central station adapted to build up a non-inductive circuit through said broken line to any desired substation, other electromagnetic mechanism controlled from said central station adapted to break said electric circuit at said substations, a return-circuit from said substations to said central station, electric signaling apparatus at each of said substations, a second line connecting all of said substations with the central station, and electromagnetic mechanism controlled from said central station adapted to connect the said second line with the signaling apparatus at any of said substations, substantially as described.

19. In combination, a central station, three lines leading therefrom to a series of substations, and electromagnetic selective apparatus at each of said substations adapted to be connected in series with one of said lines, and adapted to be connected in multiple with either of the other two lines, substantially as described.

20. In combination, a central station, three lines leading therefrom to a series of substations, one of said lines being normally broken at each substation, electromagnetic selective apparatus adapted to be connected in series with one of said lines and adapted to be connected in multiple with either of the other two lines, and electromagnetic mechanism adapted to automatically connect said selective apparatus in series with the broken line, substantially as described.

21. In combination, a central station, three lines leading therefrom to a series of substations, one of said lines being normally broken at each substation, electromagnetic selective apparatus at each of said substations adapted to be connected in series with one of said lines and adapted to be connected in multiple with either of the other two lines, and electromagnetic mechanism adapted to automatically connect said selective apparatus in series with the broken line and to automatically disconnect the multiple connection of said selective apparatus with one of the other two lines, substantially as described.

22. In combination, a central station, three

lines leading therefrom to a series of substations, one of said lines being normally broken at each substation, electromagnetic apparatus at each of said substations adapted to be connected in series with one of said lines and adapted to be connected in multiple with either of the other two lines, and electromagnetic mechanism controlled from the central station adapted to automatically connect said selective apparatus in series with the broken line, substantially as described.

23. In combination, a central station, three lines leading therefrom to a series of substations, one of said lines being normally broken at each substation, electromagnetic selective apparatus at each of said substations adapted to be connected in series with one of said lines and adapted to be connected in multiple with either of the other two lines, and electromagnetic mechanism at each of said substations controlled from the central station adapted to automatically connect said selective apparatus in series with the broken line, and to automatically disconnect the multiple connections of said apparatus with one of the other two lines, substantially as described.

24. In combination, a central station, three lines leading therefrom to a series of substations, one of said lines being normally broken at each substation, electromagnetic selective apparatus at each of said substations adapted to be connected in series with one of said lines and adapted to be connected in multiple with either of the other two lines, and neutral electromagnetic mechanism adapted to automatically connect said selective apparatus in series with the broken line, substantially as described.

25. In combination, a central station, three lines leading therefrom to a series of substations, one of said lines being normally broken at each substation, electromagnetic selective apparatus at each of said substations adapted to be connected in series with one of said lines and adapted to be connected in multiple with either of the other two lines, and neutral electromagnetic mechanism adapted to automatically connect said selective apparatus in series with the broken line and to automatically disconnect the multiple connections of said selective apparatus with one of the other two lines, substantially as described.

26. In combination, a central station, three lines leading therefrom to a series of substations, one of said lines being normally broken at each substation, electromagnetic selective apparatus at each of said substations adapted to be connected in series with each one of said lines and adapted to be connected in multiple with either of the other two lines, and neutral electromagnetic mechanism controlled from the central station adapted to automatically connect said selective apparatus in series with the broken line, substantially as described.

27. In combination, a central station, three lines leading therefrom to a series of substations, one of said lines being normally broken at each substation, electromagnetic selective apparatus at each of said substations adapted to be connected in series with one of said lines and adapted to be connected in multiple with either of the other two lines, and neutral electromagnetic mechanism controlled from the central station adapted to automatically connect said selective apparatus in series with the broken line and to automatically disconnect the multiple connections of said selective apparatus with one of the other two lines, substantially as described.
28. In a selective party-line telephone system, the combination with a series of substations, electromagnetic selective apparatus at each of said substations, a connecting line normally broken at each of said substations, a second line normally connected to the selective apparatus at each of said substations, a third line adapted to be connected in circuit with the selective apparatus at each of said substations, and neutral electromagnetic mechanism adapted to automatically connect said selective apparatus in series with the broken line, means adapted to automatically build up and restore said broken line and to break the normal connection with said second line and to connect said selective apparatus in circuit with said third line, the selective apparatus at any one substation being identical with that at all other substations, substantially as described.
29. In a selective party-line telephone system, the combination with a series of substations, of electromagnetic selective apparatus at each of said substations, a connecting line normally broken at each of said substations, a second line normally connected to the selective apparatus at each of the substations, a third line adapted to be connected in circuit with the selective apparatus at each of the said substations, and electromagnetic means controlled from the central station adapted to automatically build up and restore said broken line and to break the normal connection with the said second line, and to connect said selective apparatus in circuit with said third line, the selective apparatus at any one substation being identical with that at all other substations, substantially as described.
30. In a selective party-line telephone system, the combination with a series of substations, of electromagnetic selective apparatus at each of said substations, a connecting line normally broken at said substations, a second line normally connected with the selective apparatus at each of said substations, a third line adapted to be connected in circuit with the selective apparatus at each of said substations, and electromagnetic means adapted to automatically build up and re-
- store said broken line and to break the normal connection with said second line and to connect said selective apparatus in circuit with said third line, the selective apparatus at any one substation being identical with that at all other substations, substantially as described.
31. In a selective party-line telephone system, the combination with a series of substations, of suitable selective apparatus at each of said substations, a line connecting said substations normally broken at each of said substations, telephone instruments at each of said substations normally disconnected from said line, and means for connecting said telephone instruments in circuit with said broken line, substantially as described.
32. In a selective party-line telephone system, the combination with a series of substations, of suitable selective apparatus at each of said substations, a line adapted to connect said substations normally broken at each substation, a second line normally connected to the selective apparatus at each of said substations, telephone instruments at each of said substations normally disconnected from said lines, and means for connecting said telephone instruments in circuit with said broken line, substantially as described.
33. In a selective party-line telephone system, the combination with a series of substations, of suitable selective apparatus at each of said substations, a line adapted to connect said substations but normally broken at each of said substations, a second line normally connected with the selective apparatus at each of said substations, a third line adapted to be connected in multiple with the selective apparatus at each of said substations, telephone instruments at said substations normally disconnected from said broken line, and means adapted to connect said telephone instruments in circuit with said broken line, substantially as described.
34. The combination with a central station, of a line running from said central station broken at a series of substations, neutral electromagnetic mechanism adapted to build up a non-inductive electrical path through said broken line, a return-circuit from said substations to said central station, electric signaling apparatus at each of said substations, a second line connecting all of said substations with the central station, and electromagnetic mechanism adapted to connect said signaling apparatus in circuit with two of said lines, substantially as described.
35. The combination with a central station, of a line running from said central station broken at a series of substations, neutral electromagnetic mechanism controlled from the central station adapted to build up a non-inductive electrical path through said broken line to any desired substation, a return-circuit from said substations to said

central station, electric signaling apparatus at each of said substations, a second line connecting all of said substations with the central station, and electromagnetic mechanism controlled from the central station adapted to connect said signaling apparatus in circuit with two of said lines, substantially as described.

36. The combination with a central station, of a line running from said central station broken at a series of substations, neutral electromagnetic mechanism controlled from the central station adapted to build up a non-inductive electrical path through said broken line to any desired substation, electric signaling apparatus at each of said substations, a second line connecting all of said substations with the central station, and electromagnetic mechanism controlled from said central station adapted to connect said signaling apparatus in circuit with two of said lines, substantially as described.

37. The combination with a central station, of a line running from said central station broken at a series of substations, electromagnetic mechanism controlled from the central station adapted to build up a non-inductive path through said broken line to any desired substation, a return-circuit from said substations to said central station, electric signaling apparatus at each of said substations, a second line connecting all of said substations with the central station, and electromagnetic mechanism controlled from said central station adapted to connect one of said lines with the signaling apparatus at any one of said substations, substantially as described.

38. The combination with a central station, of a line running from said central station broken at a series of substations, electromagnetic mechanism controlled from the central station adapted to build up a non-inductive electrical path through said broken line to any desired substation, other electromagnetic mechanism controlled from said central station adapted to break said electrical path at said substations, a return-circuit from said substations to said central station, electric signaling apparatus at each of said substations, a second line connecting all of said substations with the central station, and electromagnetic mechanism controlled from the central station adapted to connect one of said lines with the signaling apparatus at any of said substations, substantially as described.

39. The combination with a central station, of a line running from said central station broken at a series of substations, neutral electromagnetic mechanism controlled from the central station adapted to build up a non-inductive circuit through said broken line to any desired substation, a return-circuit from said substations to said central station, elec-

tric signaling apparatus at each of said substations, a second line connecting all of said substations with the central station, and electromagnetic mechanism controlled from said central station adapted to connect said signaling apparatus in circuit with two of said lines.

40. The combination with a central station, of a line running from said central station broken at a series of substations, electromagnetic mechanism controlled from the central station adapted to build up a non-inductive circuit through said broken line to any desired substation, other electromagnetic mechanism controlled from said central station adapted to break said electric circuit at said substations, a return-circuit from said substations to said central station, electric signaling apparatus at each of said substations, a second line connecting all of said substations with the central station, and electromagnetic mechanism controlled from said central station adapted to connect said signaling apparatus in circuit with two of said lines, substantially as described.

41. The combination with a central station, of a line running from said central station broken at a series of substations, electromagnetic mechanism controlled from the central station adapted to build up a non-inductive circuit through said broken line to any desired substation, other electromagnetic mechanism controlled from said central station adapted to connect said signaling apparatus in circuit with two of said lines, substantially as described.

42. The combination with a central station, of a line running from the said central station broken at a series of substations, automatic mechanism adapted to build up said broken line, a return-circuit from said substations to said central station, electric signaling apparatus at each of said substations, a second line connecting all of said substations with the central station, and mechanism adapted to connect said signaling apparatus in a non-inductive circuit with two of said lines, substantially as described.

43. The combination with a central station of a line running from said central station broken at a series of substations, electromagnetic mechanism adapted to build up a non-inductive electrical path through said broken line, return-circuits from said substations to said central station, electric signaling apparatus at each of said substations, a second line connecting all of said substations

with the central station, and electromagnetic mechanism adapted to connect said signaling apparatus in a non-inductive circuit with two of said lines, substantially as described.

44. The combination with a central station, of a line running from said central station broken at a series of substations, electromagnetic mechanism controlled from the central station adapted to build up a non-inductive electrical path through said broken line to any desired substation, a return-circuit from said substations to said central station, electric signaling apparatus at each of said substations, a second line connecting all of said substations with the central station, and electromagnetic mechanism controlled from the central station adapted to connect said signaling apparatus in a non-inductive circuit with two of said lines, substantially as described.

45. The combination with a central station, of a line running from said central station broken at a series of substations, electromagnetic mechanism controlled from the central station adapted to build up a non-inductive electrical path through said broken line to any desired substation, electric signaling apparatus at each of said substations, a second line connecting all of said substations with the central station, and electromagnetic mechanism controlled from said central station adapted to connect said signaling apparatus in a non-inductive circuit with two of said lines, substantially as described. 35

In testimony whereof we have hereunto set our hands.

FRANK B. HALL.
ARTHUR F. POOLE.
